QUICK DETACHABLE CONNECTOR FOR
INTERCONNECTING TERMINALSJames J. Bulla, Morristown, N. J., assignor to
Western Electric Company, Incorporated, New
York, N. Y., a corporation of New York

Application December 24, 1948, Serial No. 67,162

4 Claims. (Cl. 173—328)

1

This invention relates to electrical connectors, and more particularly to quick detachable connectors for interconnecting terminals.

In the testing of the different sections of an electrical system, such as the component units of a radar system, it is necessary to provide a plurality of connector leads from the testing apparatus which may be easily and quickly connected to the electrical outlets of the units to be tested. Heretofore, much time was wasted in connecting and disconnecting the leads from a test cable to the several conductors of a multi-strand cable leading to or forming part of the several electrical circuits present in the units to be tested. By use of the present invention, all of the electrical circuits of the radar units can be connected with, or disconnected from, the main test cable by the simple expedient of separating a connector strip. In addition, electrical trouble shooting is facilitated inasmuch as the individual conductors, in not being soldered to the connector, may be easily and rapidly disconnected therefrom.

An object of the invention is to provide a new and improved connector for interconnecting a plurality of terminals from a test cable to permanently fixed terminals of an apparatus to be tested.

With the above and other objects in view, the invention may be embodied in a device comprising a pair of separable and identical dielectric blocks. The top portion of each block has formed thereon a plurality of parallel ribs or fins extending transversely of the block. A single metallic contact member is molded in the block between each pair of a series of ribs and provides plural connections for securing thereon the terminals of a plurality of conductors. The blocks are held together by a pair of insulated clamping screws loosely held in one of the blocks and electrical contacts are provided between the two blocks by a plurality of resilient leaf spring contacts secured to the lower portion of the upper block. The upper half terminal block is portable and is connected to a cable from the test apparatus while the other block is fixedly mounted to the apparatus under test.

A complete understanding of the invention may be obtained from the following detailed description taken in conjunction with the accompanying drawings, in which

Fig. 1 is a perspective opened view of the cooperating quick detachable connector blocks showing conductor terminals of the cables secured thereto.

2

Fig. 2 is a vertical cross-sectional view of the connector in operative closed position and showing in particular one of the insulated clamping screws for holding the blocks together;

5 Fig. 3 is a vertical cross-sectional view of the connector in operative closed position showing in particular one of the resilient contact leaf springs; and

10 Fig. 4 is a side elevational view of the resilient contact leaf spring shown in its non-compressed position.

A connector 11 is shown in perspective in Fig. 1 and consists of two molded dielectric blocks 12 and 13 each of which is identical in structure. 15 The blocks 12 and 13 have formed on their upper surfaces a plurality of upstanding ribs or fins 14 which are parallel to one another and extend transversely of the blocks. Located between each pair of ribs 14 a single figure-eight shaped flat contact metal member 15 is securely held in equally spaced holes 16 formed in the blocks 12 and 13 which holes extend through the blocks. The flat metal member 15 has two depending internally threaded portions 17 and 18 which extend about halfway into the holes 16 in the blocks. A resilient metal contact leaf spring 19 is secured to the bottom or underside of the block 12 by an upstanding internally threaded metal insert 20 riveted to the spring which insert 25 fits into hole 16 (Fig. 3). A round head machine screw 21 secures the insert 20 in the hole 16 by engaging the internal threads of the insert. The internal diameter of the threaded portion 17 is larger than the diameter of the screw 21 and as a result of this tolerance the spring 19 is held tightly against the block 12. A lock washer 22 (Fig. 3) placed under the head of the screw 21, prevents the latter from turning once 30 it is tightened.

40 One end of each spring 19 has an upturned edge 23 which overlaps the bottom forward edge of the block 12 (Fig. 3) to properly position the spring and prevent it from longitudinal movement. The other end of spring 19 is zigzag-shaped (Fig. 4) and contacts the metal member 15 in the under block 13 when the two blocks are held together, one on top of the other. In 45 coming into contact with the metal strap member 15, the depending edge or lug 24 of the zig-zag-shaped part of the spring 19 in block 12 wipes the upper surface of the member 15 in block 13 and thereby insures a positive electrical contact between the two. The interchangeable contact spring assemblies 19 are easily removed

50 and replaced by removing screw 21 and pulling 55

the inserts 20 from the apertures 16 in the block 12.

The lower block 13 (Figs. 2 and 3) may be permanently secured to a panel or a wall 25 (Fig. 1) of an electrical apparatus to be tested by four screws 26 which are located at the right and left ends of the block as viewed in Fig. 1. A cable 27 of the apparatus under test is electrically connected to the block 13 by a plurality of flat terminals 28 which are crimped to the individual ends of a plurality of conductors 29 of the cable 27. These terminals 28 are held in electrical contact with the metal strips 15 in the block 13 by the screws 24. Since all of the conductors 29 extend transversely from the top of the block 13, rather than protrude from the underside, the block may be permanently mounted on any flat surface.

The portable connector block 12 is connected to the testing apparatus by a cable 30 in the same manner as the cable 27 is connected to block 13, and similarly the cable 30 consists of a plurality of conductors 31, each having flat connecting terminals 32 crimped thereto.

When it is desired to test an electrical apparatus connected through the cable 27 to the terminal block 13, the portable upper block 12 is placed on top of the lower block 13 and is fastened thereto by two insulated clamping screws 33, each of which have an intermediate small shank portion 34 of smaller diameter than the internal diameter of the threaded portion 18 whereby the screw 33 is loosely retained in the block 12 when not in use. The lower threaded portions of the screws 33 engage the threads of the depending portions 18 of strap members 15 in the lower block 13. As the thumb screws 33 are tightened, the blocks 12 and 13 are gradually pulled closer together whereby the lowermost edges of the connector leaf springs 19 are forced to wipe over and make good contacts with the upper surface of the flat metal members 15 (Fig. 3.) Thus by placing the connector block 12 on top of the block 13 and tightening the clamping screws 33 a plurality of quickly made circuits are established through an electrical apparatus under test through cable 27, terminals 28, contact members 15 in block 13, leaf springs 19, inserts 20, screws 24 (Fig. 3), contact members 15 in block 12, terminals 32 and cable 30 through the testing apparatus. In this manner, positive electrical contacts are assured between the connector blocks 12 and 13 and circuit tracing is facilitated by having detachable terminals 28 and 32 which may be removed simply by loosening the screws 24.

It is to be understood that the above-described arrangement is simply illustrative of the application of the principles of the invention and that numerous other arrangements may be readily devised by those skilled in the art which will embody the principles of the invention and fall within the spirit and scope thereof as defined by the appended claims.

What is claimed is:

1. In a quick detachable electrical connector, a pair of similar and interchangeable dielectric blocks, one of said blocks being stationary and the other portable, a plurality of contacts molded in each of said blocks, means associated with each contact for detachably fastening a conductor to the contact, a plurality of projecting barrier ribs formed in the top of each block and extending transversely thereof between each contact, a spring member secured to each contact on the underside of the portable block by an insert

attached to the member immediately below the contact, said spring members having a zigzag-shaped portion with a lug formed thereon, and loosely held means in the portable block for clamping the blocks together whereby the lugs of the spring members are forced to wipe a portion of the molded contacts in the stationary block to electrically interconnect the contacts in the portable block with the corresponding contacts in the stationary block.

2. In a quick detachable connector for interconnecting a plurality of conductors, a pair of similar and interchangeable dielectric blocks having spaced apertures therethrough, each of said blocks having a series of similar transverse sections, a metallic contact molded into each section and having an aperture extending from the top to the bottom face thereof and in alignment with one of said apertures in a block, dielectric barrier ribs formed in the top of each of the blocks and extending transversely between said sections, means associated with each contact for detachably fastening a conductor to the contact, a projecting spring member detachably secured to each contact on one of the blocks on the underside thereof by an insert fitting into one of the apertures in the said block, and means fitting within apertures in one of the blocks and passing through apertures in the other block to clamp the blocks together whereby the spring members electrically interconnect the corresponding contacts in the blocks.

3. In a quick detachable connector, a pair of similar and interchangeable dielectric blocks having spaced pairs of apertures therethrough, one of said blocks being stationary and the other portable, each of said blocks having a series of similar transverse sections, a metallic contact molded into each section and having a pair of apertures extending from the top to the bottom face thereof, dielectric barrier ribs formed in the top of each of the blocks and extending transversely thereof between each of the contacts to define and isolate said sections, means associated with each contact and fitting within one of said apertures in the block and passing through one of the apertures in said contact to detachably fasten a conductor to the contact, a projecting spring member detachably secured to each contact on the portable block on the underside thereof by an insert fitting within another aperture in the block, means passing through said insert and through the other aperture in the molded contact for electrically connecting the contact and said spring member, and means passing through apertures in the portable block and fitting within apertures in the stationary block to clamp the blocks together whereby the spring members electrically interconnect the contacts in the portable block with the corresponding contacts in the stationary block.

4. In a quick detachable connector for interconnecting a plurality of conductors, a pair of similar dielectric blocks having spaced pairs of apertures therethrough, dielectric barrier ribs positioned on top of each of the blocks to form a plurality of transverse sections thereon, a metallic contact molded into each of said sections and having a pair of apertures extending therethrough in alignment with the one pair of apertures in said block, means fitting within the first aligned aperture for detachably fastening a conductor to each of the contacts, a projecting spring member detachably secured in each of said transverse sections to the underside of one

of the blocks by an insert fitting within one of the apertures in said block, said spring member having a depending end portion at right angles to the body of the spring, means fitting within said insert and passing through the second aligned aperture for making an electrical connection between the contact and the spring member, and means positioned in one of the blocks for clamping the blocks together to force the depending end portions of said spring members to wipe a portion of the contacts in the other block to provide electrical connections between the blocks.
